F. A. OHRENSCHALL.

BOTTLE STAND.

No. 15,918.

Patented Mar. 3, 1885.

UNITED STATES PATENT OFFICE.

FREDERICK A. OHRENSCHALL, OF BALTIMORE, MARYLAND, ASSIGNOR TO
JOHN H. WINKELMANN, OF SAME PLACE.

DESIGN FOR A BOTTLE-STAND.

SPECIFICATION forming part of Design No. 15,918, dated March 3, 1885.

Application filed November 7, 1884. Term of patent 3½ years.

To all whom it may concern:

Be it known that I, FREDERICK A. OHRENSCHALL, a citizen of the United States, residing at the city of Baltimore, in the State of Maryland, have invented and produced a new and original Design for a Bottle-Stand, of which the following is a specification, reference being had to the accompanying photograph, forming part thereof. Said photograph sufficiently represents my design, which is a bottle-stand in the general form of a chair. The illustration is a nearly front view, so as to show one side or end and the four legs, and the leading features of my design, as herein-after more fully referred to, viz:

A is the back, in the middle part of which is a circular space within the rim or beading α , showing the representation of a dial and

hands of a clock or watch, B, inserted therein. C is the seat, perforated with circular holes in rows. D is a board placed parallel with the perforated seat. E is a circular piece.

I claim—

The design for a bottle-stand herein shown and described, the same consisting of the representation of a chair having a circular rim or beading, α , within which is the representation of the dial and hands of a clock or watch, B, with the seat C, perforated with circular holes in rows, and the board D and the circular piece E.

FREDERICK A. OHRENSCHALL.

Witnesses:

JOSEPH S. RIDER,
W. GRAFTON MASON.
